UNITED STATES PATENT OFFICE.

WILLIAM WESTPHAL, OF LOS ANGELES, CALIFORNIA.

DAVENPORT WALL-BED.

1,121,543.

Specification of Letters Patent. Patented Dec. 15, 1914.

Application filed November 19, 1912. Serial No. 732,385.

To all whom it may concern:

Be it known that I, WILLIAM WESTPHAL, a citizen of the United States, residing at Los Angeles, in the county of Los Angeles and State of California, have invented a new and useful Davenport Wall-Bed, of which the following is a specification.

This invention relates to a bed of the type known as a davenport bed that is adapted to 10 be folded to serve as a sofa or lounge when not in use as a bed and includes a davenport which is capable of being built into the wall as a wall bed and is also capable of being detached from the wall and simply placed 15 against the same as with a common davenport bed.

An object of this invention is to provide a davenport bed which can be opened and closed with minimum labor; which will have 20 an uninterrupted spring support when opened in bed form; and which will give a broader bed surface when opened than heretofore provided for davenport beds having the same width of seat and height of back 25 when closed.

A further object of the invention is to provide a davenport bed in which the connecting means between the seat back frame and base may with facility be completely 30 concealed from view, thus annihilating the possibility of injury to the attendant or to children from the exposed connecting means when the seat back frame is being moved.

A still further object of the invention is to 35 provide a davenport bed in which the connecting means between the seat back frame and base can with facility be concealed from view to add to the appearance of the device.

Another object is to construct a davenport 40 bed which can be opened and closed with minimum movement of the hand.

A further object is to make a davenport having the foregoing advantages and being light and easy to handle, to open and close 45 and to move about.

The accompanying drawings illustrate the invention.

Figures 1 and 2 are front and end elevations respectively, of the invention as embodied in the form of a davenport bed applied in seat form against a wall, a portion of which is shown in sectional elevation. 50 Figs. 3 and 4 are front and end elevations analogous to Figs. 1 and 2, respectively, 55 showing the invention applied as a built-in

wall bed. Figs. 1 and 3 are in reduced scale. Fig. 5 is a broken end elevation of a davenport bed constructed in accordance with this invention and viewed from line x^5-x^6 , Figs. 8 and 9, looking in the direction of the arrows. Solid lines show the bed in seat form, while dot and dash lines indicate a position assumed by parts while they are being turned into bed form. Fig. 6 is an elevation partly in section viewed from line x^5-x^6 , 65 Figs. 8 and 9, the device being shown in bed form in solid lines while dot and dash lines indicate a position of parts just before reaching said bed form. Fig. 7 is a fragmental enlarged perspective detail illustrating a feature of the operating levers. Fig. 8 is a plan view showing parts in bed form with the mattress folded and strapped upon one of the frames preparatory to turning the frames into seat form. Fig. 9 is a 70 broken longitudinal section viewed from line x^9 , Figs. 2 and 5, with parts in seat form.

Broadly considered, the invention comprises a pivotally mounted reversible back 80 frame 1 that serves as a back for a seat and is convertible by movement on its pivot into a frame for a bed bottom; a pivotally mounted reversible seat frame 2; said frames being mounted and connected together to turn simultaneously to change the device from bed form into seat form and vice versa, there being means connecting the lower ends of the back frame with the seat frame to cause the one to simultaneously turn with the other from their respective normal positions at rest, said means having pivotal connection and being entirely positioned at a level lower than the base of the seat when the back frame is in erect position as will 90 now be more fully explained. As a support for the back frame 1 and seat frame 2 there is provided a base 3 having a box-like chamber 4 that is bounded by a front piece 5, end pieces 6 and a floor 7. To the said base 95 there is hinged by hinges 8 at the tops and rear edges of the end pieces 6 a convertible back, and bed bottom frame 1. Said frame 1 is provided with a seat-back cushion 9 on one side and a section of bed springs 10 on the other side. A space 11 behind the base is closed at the top by a top piece 12 extending across between end portions 13 and 14 that are secured to the end pieces 6 by means of bolts 15. Said end portions 13 and 110

14 may be upholstered or otherwise constructed and are adapted to continue forwardly adjacent the end pieces 6 of the base 3 to form arm rests 16 and 17, as shown in 5 Figs. 3 and 5; and the frame 1 carrying the springs 10 is adapted to extend either vertically between the end portions 13 and 14 to close the space 11 at the front thereof when the frame 1 is in position to form the seat-back, or horizontally between the 10 arm rests 16 and 17 when the device is adjusted to form a bed.

To the top of the front piece 5 of the base 3 is hinged at one edge by hinges 18 the 15 convertible seat and bed-bottom frame 2 that is provided on one side with a resilient cushion seat 19 and on the other side with a section of bed springs 20. It is thus seen that the reversible back frame is hinged to 20 said base by hinges 8 at one side thereof and that the reversible seat frame 2 is hinged by hinges 18 to the base at the other side thereof and at a higher level than the back frame is hinged. Said frame 2 with 25 its seat and bed springs is adapted to extend horizontally between the end portions 13 and 14 upon the inside of the front piece 5 when in seat form and horizontally in an inverted position upon the other side of the 30 front piece when in bed form.

The free edge of the frame 2 is provided with the flexible loop *a* by which it may be manipulated in the operation of opening and closing the bed.

35 A mattress 21 is adapted to be folded and strapped upon either of the spring sections 10 or 20 to the frames 1 and 2 respectively, preferably upon the seat and bed bottom frame 2, and to this end I provide a plurality of straps 22 secured to one side of said frame 2 and adapted to extend over the mattress 21 and into engagement with hooks 23 mounted upon the other side of the frame.

45 Compound lever connecting means are provided between the base 3 and the frames 1 and 2 to transmit motion from one to the other of said frames. Said means are corresponding sets of levers mounted at the ends 50 of the bed between the inside of the arm rests 16 and 17 and the end pieces 6; and to provide space for the operation of said means a filler block 24 is interposed and clamped in place by the bolts 15 between 55 said arm rests and the end pieces 6 at each end of the bed.

The connecting means between the base and the frame 1 upon either end of the bed comprises a fulcrum link 25 pivoted at 26 to 60 the end piece 6 of the base 3 and a connecting link 27 pivoted to the frame at 28, the free extremities of said fulcrum link and connecting link being pivoted together by pivot 29. The connecting means between 65 the base and the seat frame 2 comprises a

collapsible connection 30 consisting of a member 31 pivoted at 32 to the end piece 6 of the base 3, a member 33 pivoted to the seat frame at 34, and a pivot 35 connecting said members 31 and 33. Means are provided to connect the pivots 35 and 29 comprising a support 37 pivoted to the base at 38, a link 39 having one end mounted on the pivot 35 and the other end on pivot 40 at the upper end of said support 37, and 75 a connecting bar 41 between the pivot 40 and the pivot 29.

A stop 42 is provided upon the member 33 adjacent the pivot 35 adapted to engage the link 39 to arrest the alining movement 80 of the members 31 and 33 as the frame 2 is turned on its hinge 18. In order to gain the most direct and precise action of parts in the form illustrated in this application, it is desirable that the link 39 be practically 85 horizontal at all times and to this end the pivots 32, 38, 35 and 40 are arranged at the corners of a parallelogram so that as the arms 31 and 37 are moved forward or backward as hereinafter described upon 90 their pivots 32 and 38 the link 39 remains parallel with the pivots 32 and 38 that are substantially in parallel alinement with the floor 7.

A supporting plate 43 is secured to the 95 bed spring side of the frame 2 at the ends thereof, extends outwardly therefrom, and is adapted to seat on the points formed at the pivots 29 between the fulcrum links 25 and connecting links 27 at the ends of the 100 bed, to thereby support the frame 2 in its seat form as shown in Figs. 5 and 9.

Means are provided to support the seat frame 2 in its bed form comprising legs 44 pivoted at 44' at the ends of the frame; said 105 legs being provided with slots 45 in which are slidably mounted pivot ends of connecting rods 46 pivoted at their other ends to the members 33 between the pivots 34 and 35 thereof.

At the ends of the frame 2 are provided brackets 47 upon which the legs 44 are adapted to rest when in the folded position they assume whenever the member 2 is in 110 seat form.

Spring means to ease the frames 1 and 2 into seat or bed form are provided preferably in the form of a helical spring 48 that may be attached to the frame 1 and base floor 7 by means of screw eyes or staples 49 115 and 50 respectively.

The hinges 8 for the convertible seat back frame 1, are located above the bottom edge of said frame so that when the back is in upright position, the height of the back above the base will not be the full width of the frame but when in bed position, the full width of the frame will be used. This is of 125 advantage as it may not be desired to have a high seat back and in this manner, the width 130

of the bed need not be decreased in order to obtain a seat back of proper height. Furthermore, the spring 48 is connected to the lower edge of said frame 1 considerably below the hinge 8 so as to have as great leverage as possible upon said frame to assist in counterbalancing the parts as operation thereof is effected.

When the bed is folded in seat form the 10 legs 44 rest upon the brackets 47, and support the connecting rods in folded position as shown in Fig. 5; and the frame 2 with the mattress attached thereto is supported on the joint formed by the pivot 29 upon which 15 the bearing plate 43 rests; said mattress being housed in the chamber 4 that is provided for that purpose.

The frame 1 with its spring section 10 stands on edge between the end-positions 13, 20 14 to close the recess 11 when the device is in seat form.

In practical operation the device may be turned from seat form into bed form by pulling up the loop *a* thereby turning the 25 frame 2 on the hinges 18. This movement increases the distance between the pivots 34 and 32 causing the members 31 and 33 to swing rearwardly about their pivots 32 and 34 toward an alined position with one 30 another, thereby moving the pivot 35 rearwardly, and acting through the connections 39, 37 and 41 in turn moving the pivot 29 to extend the frame 1 backwardly upon its 35 hinges 8 and into the space 11. This backward movement of the member 1 acts only as a compensating movement while the member 2 is being substantially raised on edge as indicated by dot and dash lines in Fig. 5; and as the movement of the joint at the 40 pivot 35 continues by reason of the further turning of the member 2, the stop 42 engages the under side of the link 39 to prevent the members 33 and 31 from coming into alinement with one another, thereby 45 arresting the rearward movement of the pivot 35, and upon a still further turning movement of the member 2 moves the pivot 35 forwardly by collapsing the members 31 and 33 as the distance between the pivots 32 50 and 34 decreases. This forward movement of the pivot in turn acts upon the pivot 29 through the said connections 39, 37 and 41 to bring the member 1 forwardly upon its 55 hinges 8 until arrested by the end pieces 6 of the base. During this time the frame 2 with folded mattress attached thereto, has been turned into the horizontal position shown by solid lines in Fig. 6, and the leg 44 has arrived in position to support the frame 2, 60 having been extended into said position during the downward movement of the frame 2. With the frames 1 and 2 now opened into bed form, the folded mattress 21 may be unstrapped from the springs 20 of the frame 2 65 and the folded over portion laid upon the

springs 10 of the frame 1, thereby forming a bed with an uninterrupted spring support and mattress thereon.

When it is desired to turn from bed form back into seat form, the operation just described is reversed.

The construction of the operative parts is practically the same in the detached as in the built-in construction, there being in the latter, a recess 148 being formed in the wall 75 149 to receive the seat-back and bed bottom portion; and the arms being fixed to the wall.

It is understood that various forms of means connecting between the frames 1 and 2 may be provided to cause the one to simultaneously turn with the other and this invention is regarded as pioneer in that the seat-back and the seat bottom are connected to simultaneously turn from seat form to bed 85 form as herein disclosed.

I claim:—

1. In a bed, a pivotally mounted reversible back frame, a pivotally mounted reversible seat frame, and means connecting the 90 lower ends of the back frame with the seat frame to cause the one to simultaneously turn with the other from their respective normal positions of rest, said means having pivotal connections and being entirely positioned at a level lower than the face of the seat when the back frame is in erect position.

2. A base having a front piece of greater height than the rear edge of the base; a reversible seat-back frame hinged adjacent its rear edge to said base at said rear edge; a reversible seat frame of substantially the same width as the base hinged at one edge to the upper edge of the front piece; the hinges of 100 the seat-back frame and of the seat frame being positioned to bring the seat-back frame, seat frame and the upper edge of the front piece flush with one another when the seat-back frame is closed over the base; 105 and means connecting the seat-back frame and seat frame together for simultaneous turning of said frames on their hinges.

3. A base, a reversible back frame hinged to the base at one side thereof, a reversible 115 seat frame hinged to the base at the other side thereof and at a higher level than the seat back frame is hinged, and connecting means connecting the lower ends of the back frame with the seat frame adapted to be actuated by the seat frame alone, to simultaneously turn said back frame into seat back form as said seat frame is turned into seat form, said means having pivotal connections and being entirely positioned at a level 120 lower than the face of the seat when the back frame is in erect position, and spring means connecting said seat frame with said base to counterbalance the frames.

4. A base, a reversible seat-back frame 130

- 1 hinged to the base at one side thereof to move about a fixed pivotal point, a reversible seat frame hinged to the base at the other side thereof to move about a fixed pivotal point, a connection between the base and the seat-back frame, a collapsible connection between the base and the seat frame, and connecting means between said connections.
- 5 5. A base, a reversible seat-back frame hinged to the base at one side thereof to move about a fixed pivotal point, a reversible seat frame hinged to the base at the other side thereof to move about a fixed pivotal point, a connection between the base and the seat-back frame comprising a fulcrum link pivoted to said base, a connecting link pivoted to the seat back frame, said fulcrum and connecting links being pivoted together and adapted to form a stop for the seat frame, a collapsible connection between the base and the seat frame, and connecting means between said fulcrum link and connecting link and said collapsible connection.
- 10 6. A base, a reversible seat-back frame hinged to the base at one side thereof to move about a fixed pivotal point, a reversible seat frame hinged to the base at the other side thereof to move about a fixed pivotal point, a connection between the base and the seat back frame, a collapsible connection between the base and the seat frame comprising a member pivoted to said base, a member pivoted to said seat frame, a pivot connecting said members, and connecting means between said pivot and said base and seat back connection.
- 15 7. A base, a reversible seat-back frame hinged to the base at one side thereof to move about a fixed pivotal point, a reversible seat frame hinged to the base at the other side thereof to move about a fixed pivotal point, a connection between the base and the seat-back frame, a collapsible connection between the base and the seat frame comprising a member pivoted to said base, a member pivoted to said seat frame, a pivot connecting said members, connecting means between said pivot and said base and seat-back connection, a stop on one of said members adjacent the pivot and adapted to engage the connecting means.
- 20 8. A base, a reversible seat-back frame hinged to the base at one side thereof to move about a fixed pivotal point, a reversible seat frame hinged to the base at the other side thereof to move about a fixed pivotal point, a connection between the base and the seat-back frame, a collapsible connection between the base and the seat frame, connecting means between said connections, arresting means for said seat-back frame, and supporting means for said seat frame comprising foldable legs pivoted thereto.
- 25 9. A base, a reversible seat-back frame hinged to the base at one side thereof to move about a fixed pivotal point, a reversible seat frame hinged to the base at the other side thereof to move about a fixed pivotal point, a connection between the base and the seat-back frame, a collapsible connection between the base and the seat frame, connecting means between said connection, arresting means for said seat-back frame, brackets upon said seat frame, and supporting means for said last named member comprising foldable legs pivoted thereto and adapted to fold upon said brackets.
- 30 10. A base, a reversible seat-back frame hinged to the base at one side thereof, a reversible seat frame hinged to the base at the other side thereof, a connection between the base and the seat-back, a collapsible connection between the base and seat comprising a member pivoted to said base, a member pivoted to said seat, a pivot connecting said members, connecting means between said pivot and said base and seat-back connection, arresting means for said seat-back, brackets upon said seat, and supporting means for said last-named member comprising foldable legs pivoted thereto and adapted to fold upon said brackets.
- 35 11. A base, a reversible seat-back frame hinged to the base at one side thereof, a reversible seat frame hinged to the base at the other side thereof, a connection between the base and the seat-back, a collapsible connection between the base and seat comprising a member pivoted to said base, a member pivoted to said seat, a pivot connecting said members, connecting means between said pivot and said base and seat-back connection, arresting means for said seat-back, brackets upon said seat, and supporting means for said last-named member comprising slotted legs, connecting rods pivoted to the collapsible connection and having pivoted ends adapted to slide in said slotted legs as the same are folded or unfolded upon the brackets.
- 40 12. In testimony whereof, I have hereunto set my hand at Los Angeles, California, this 13th day of November, 1912.
- 45 WILLIAM WESTPHAL.
